United States Patent Office

Des. 210,444

Patented Mar. 12, 1968

210,444

BOTTLE

Andres Sancho Cortina, Barcelona, Spain, assignor to Andres Sancho, S.A., Barcelona, Spain

Filed Dec. 13, 1966, Ser. No. 5,020

Term of patent 14 years

(Cl. D9—54)

Fig. 1

Fig. 2

Fig. 3

Fig. 4

FIG. 1 is an elevational view of a bottle showing my new design;

FIG. 2 is another elevational view looking from the left of FIG. 1, the side opposite that shown being the same in appearance;

FIG. 3 is another elevational view looking from the left of FIG. 2; and

FIG. 4 is a top plan view thereof.

I claim:

The ornamental design for a bottle, as shown and described.
